United States Patent Office.

LOUIS RASTETTER AND ABRAHAM SIMCOX, OF FORT WAYNE, INDIANA.

Letters Patent No. 65,117, dated May 28, 1867; antedated May 16, 1867.

IMPROVED SHANK-LASTER.

The Schedule referred to in these Letters Patent and making part of the same.

TO ALL WHOM IT MAY CONCERN:

Be it known that we, LOUIS RASTETTER and ABRAHAM SIMCOX, of Fort Wayne, in the county of Allen, and State of Indiana, have invented certain new and useful Improvements in Shank-Lasting; and we do hereby declare that the following is a full, clear, and exact description thereof, reference being had to the accompanying drawings, and to the letters of reference marked thereon, in which—

Figure 1 is a sectional view.

Figure 2 is a side elevation.

The nature of our invention consists in constructing an apparatus for the purpose of shank-lasting boots, &c., which is accomplished by the combination of a self-regulating fulerum and suitable clamping-jaws, and a lever which serves as a handle.

To enable others skilled in the art to make and use our invention, we will proceed to describe its construction and operation.

A represents a shank, the upper end of which is provided with a male screw, *a*, and is inserted in female screw *b*, which is formed in the socket in the lower end of the handle B. C represents a stationary clamping-jaw, made in the form seen in the drawings, and is permanently secured to the lower end of shank A. The upper surface of said jaw is roughened, as seen at *c*, and is provided with a recess, through which a tack may be inserted into the leather for the purpose of securing the same. D represents a self-adjusting fulerum, which is pivoted to stationary jaw C, just back of shank A, by means of ears *d*, which fit into recesses *f f*. *g* represents a projection formed by cutting away the metal in forming the recess *f*, and serves as a stop to fulerum D, as will be more fully explained. Fulerum D is so curved that it may fit snugly to the under surface of clamping-jaw C, when required. The end *h* of fulerum D is curved downward and forked, so that it may take hold of the surface of the leather forming the insoles of boots or shoes. E represents a movable clamping-jaw, constructed in the form seen in the drawing, having its outer end formed, recessed, and roughened so as to fit the upper surface of stationary jaw C. Said jaw is also provided with a recess, *i*, in which is inserted a spiral spring, *j*. Said spring rests on the upper surface of jaw C, and serves to force the two jaws apart, when required. Jaw E is provided with another aperture, K, through which shank A fits loosely. Surface *l* corresponds to the surface of the base of the handle. That portion of the jaw through which shank A passes, nearly fills the space between the upper surface of the jaw C and the lower end of the handle B. Handle B is constructed of solid cast metal, in the form shown in the drawings, and serves as a lever when the instrument is in operation; also serves to retain, by its weight, said lever in position.

The operation of our invention is as follows: Turn handle B so as to unscrew shank A, which relieves jaw E. Said jaw is then thrown upward by spiral spring *j*; then pass the clamping-jaws over the edge of the leather to be operated upon; then screw down the handle on to the shank, and thus press the jaws firmly on to the leather; then place points *h* of fulerum D in the position seen in fig. 2. Next press the handle backward until the fulerum D lowers the apparatus with the portion of the leather grasped to the position seen in fig. 1; then insert a tack into the leather through the recess *m*, after which remove the apparatus by unscrewing the handle, and proceed as before.

What we claim as new, and desire to secure by Letters Patent, is—

The shank A, handle B, stationary jaw C, movable jaw E, spring *j*, adjustable fulerum D, combined and operated as described, and constructed in the manner and for the purpose specified and set forth.

LOUIS RASTETTER,
ABRAHAM SIMCOX.
